DOOR CATCH

Alvar N. Johnson, Oakland, Calif.

Application February 23, 1935, Serial No. 7,868

1 Claim. (Cl. 292—76)

The invention relates to spring catches or fasteners for doors, drawers and other swinging or sliding closures for holding the door or closure in closed or other position.

5 An object of the invention is to provide a catch of the character described in which the co-acting portions thereof are arranged to be mounted on the opposed abutting surfaces of a door and casing therefor whereby the force applied to said portions in effecting the engagement and disengagement thereof will be directly aligned with and resisted by the supports for said portions.

10 Another object of the invention is to provide a door catch of the character described which will provide for the attachment of a door pull or the like directly to one of the fastening means whereby the force applied to such pull for engaging and disengaging the catch will be transmitted directly to said member independent of the door.

15 A further object of the invention is to provide a door catch of the character above which will include an improved arrangement of a spring keeper in one of the fastener means.

20 The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claim.

25 Referring to said drawing:

Figure 1 is a sectional view of a catch constructed in accordance with my invention and shown operatively mounted on a door and casing therefor.

30 Figure 2 is a sectional view similar to Figure 1 but showing the door in closed position.

Figure 3 is a sectional view of one of the fastener members taken substantially on the plane of the line 3—3 of Figure 2.

35 Figure 4 is a sectional view similar to Figure 3 but showing a modified arrangement of the spring keeper.

Figure 5 is a sectional view similar to Figure 1 but showing a modified arrangement of the elements.

With reference to the drawing, the door catch 6 here shown comprises a pair of fastener members 1 and 8 which in accordance with the present invention are mounted directly on a pair of opposed abutting sides 9 and 11 of the door and

usual casing therefor. Thus, on closing the door the members are brought into face to face contact with each other rather than moved one by the other as is commonly the case in the usual door latch installation where one of the latch members is mounted on a side of the casing opposite the end of the door and the other latch member is carried on the end of the door and slides against the first member into a locked engagement therebehind. As will be understood, 5 the fastener members may be mounted on substantially any pair of abutting surfaces on the door and casing, but usually it is preferable that these members be installed adjacent the free swinging end of the door. Where the catch is 10 to be used in connection with a sliding drawer or the like where no pivot or lever action is present, 15 the same may be installed between substantially any pair of opposed surfaces on the drawer and support therefor.

20 As here shown, the fastener means include cylindrical shaped body portions 12 and 13 which are arranged to be mounted in suitable recessed openings 14 and 16 provided in the opposed surfaces 11 and 9. The members are preferably securely held in the recessed openings against 25 forceful withdrawal therefrom by means of a set of longitudinally spaced peripheral burs 17 and 18 and are provided adjacent their outer ends with stop flanges 19 and 21 which are arranged 30 to lie substantially flush with the surfaces 9 and 11.

35 Formed integrally with the member 8 and extending longitudinally from the outer end thereof is a knobbed projection 22 which is arranged for entry into a recess 23 in the member 7 and into operative engagement with a spring keeper 24 carried in said recess. As here shown, the keeper is mounted against longitudinal displacement in the recess by means of an annular 40 retainer groove 26 formed in the side wall of the recess, and, as may be best seen from Figure 3, the keeper may be inserted into or removed from the groove through a side opening 27 in the member 7. The keeper is of generally annular shape 45 and is arranged on initial engagement with the projection 22 to be resiliently spread by the latter and to spring into a reduced portion 28 formed in the projection to the rear of the forward end thereof.

50 As will thus be understood, the fastener members are arranged to be moved into and from engagement by a straight longitudinal or end to end movement such as provided for by their mounting between a pair of opposed abutting 55

surfaces 9 and 11. In order that on drawing apart of the fastener members no unnecessary strain will need be placed on the door, I prefer to connect a door pull 29 directly with the rear 5 of the fastener member 8 carried by the door so that the force applied to the pull 29 will be transmitted directly to the member 8 rather than to an adjacent portion of the door. Means of connection between the pull and the fastener 10 member here include a stem 31 secured to the knob 29 and extending through the side 32 of the door opposite the side 9 and into threaded engagement in a bore 33 formed in the rear side 34 of the member 8. In order that the fastener 15 members 7 and 8 may be interchangeably mounted on either the door or the casing, the member 7 is provided with a threaded bore 36 similar to bore 33 so as to enable the use of this member, as well as the member 8, in the door and its 20 connection with the stem 31 as aforesaid.

In Figure 4 there is illustrated a slightly modified form of the spring keeper. As here shown, the fastener member 7' is formed on one side thereof with a pair of spaced transverse openings 25 41 and 42 which support the sides of the U shaped spring member 24', while the free ends 43 and 44 of the spring are engaged in an opposed side opening 46 in the member 7' and held therein against longitudinal displacement. Preferably the sides 30 of the spring are interconnected at their other ends by a side 47 which is inset into a recess 48

formed in the periphery of the member 7' between the openings 41 and 42 and is preferably soldered or peened or otherwise secured therein.

In Figure 5, I have shown a slight rearrangement of the elements both as to structure and positioning. As here shown, the fastener member 7' is mounted in the door rather than in the casing, as in the previous embodiment, and is arranged to be retained in the door opening 16' by means of threads 51 provided about the periphery 10 of the body portion thereof. In order to facilitate the mounting of this member, the stop flange 21' 15 may be formed of polygonal shape so as to afford gripping thereof in a wrench or the like for turning. Also in the arrangement here shown, the door pull 29' and the stem 31' are secured to the door at a point removed from the fastener members.

I claim:

In a door catch of the character described, a 20 keeper for receiving and holding a fastener member having a headed projection, said keeper having a body portion provided with a bore opening 25 to an end thereof for receiving said projection and being formed with an annular retaining groove in said bore and a side opening registering with said groove, and a wire spring insertable 25 through said opening and sprung into said groove for resiliently engaging said projection.

30
ALVAR N. JOHNSON.
